WELDING TORCH CARRIER WITH A STORAGE RECEPTACLE OR THE LIKE

Daniel E. McCue, Santa Barbara, Calif., assignor to
Cleanweld Products, Inc., Alhambra, Calif.

Filed July 12, 1973, Ser. No. 378,630

Term of patent 14 years

Int. Cl. D8—05

U.S. Cl. D8—71

FIG. 1.

FIG. 3.

FIG. 2.

FIG. 4.

FIG. 1 is a top plan view of a welding torch carrier with a storage receptacle, showing my new design;

FIG. 2 is a side elevational view thereof;

FIG. 3 is a front elevational view thereof; and

FIG. 4 is a rear elevational view thereof.

The tubular frame and the front storage receptacle are symmetrical about a central vertical plane.

I claim:

The ornamental design for a welding torch carrier with a storage receptacle or the like, substantially as shown and described.
